HIS ATTORNEY

UNITED STATES PATENT OFFICE.

LEO H. HEIMERDINGER, OF OAK LANE, PENNSYLVANIA, ASSIGNOR TO PIONEER SUS-PENDER COMPANY, A CORPORATION OF PENNSYLVANIA.

GARTER.

Application filed November 10, 1920. Serial No. 422,994.

To all whom it may concern:

Be it known that I, LEO H. HEIMERDINGER, a citizen of the United States, residing at Oak Lane, in the county of Montgomery,

5 State of Pennsylvania, have invented a new and useful Garter, of which the following is a specification.

My invention relates to improvements in garters, especially of the class used in supporting half hose, and comprising means 10 for securing the hose at two separated points.

The object is to provide a garter having means for connecting hose supporting clasps, 15 which are adapted to engage the sock at separated points, with the leg band in such way as not to cause uneven strains and thus distort or otherwise render the garter uncomfortable to the wearer.

20 The drawing which illustrates merely by way of example suitable means for effecting my invention, is a view in perspective of the garter in the operative position.

The leg band 1 is preferably of the wide 25 web type and has secured thereto the pads or connectors 2 and 3. The pad-connector 3 is provided with the clasp member 4, secured to the pad 3 in the usual way. The clasp 5 is connected to the extension 6 which,

30 in turn is connected to the lower end of pad-connector 2. A substantial space of leg

band, 7, is provided between pad-connector 2 and 3. The free end of leg band 1 is provided with the loop or other catch member 8 adapted to cooperate with the stud or connecting member 9 for securing the free end of leg band 1 to the pad-connector member 3.

In operation, the garter is so disposed as to bring the pad-connector 3 and clasp 4 near the front of the wearer's leg, while the pad-connector 2 is located on the ball of the calf, and at an elevation somewhat above that of pad 3. In order that there shall not be undue tension and distortion of the leg 40 band approximate pad 2 and consequently of the stocking at the point of attachment of clasp 5, the extension 6 is provided to compensate for this difference in elevation between pads 2 and 3. 50

What I claim is:—

In a garter, the combination of a leg band adapted to encircle the leg in a plane substantially inclined to the horizontal, a plurality of stocking clasps and supporting 55 means therefor secured to the leg band, the supporting means being of different lengths, in order to compensate for said inclination of the leg band, to support the clasp in substantially the same horizontal plane.

LEO H. HEIMERDINGER.
